UNITED STATES PATENT OFFICE.

RAYMOND G. HANNA, OF NEW YORK, N. Y.

TWIN-SADDLE ATTACHMENT FOR MOTOR-CYCLES.

1,154,308.

Specification of Letters Patent. Patented Sept. 21, 1915.

Application filed November 17, 1914. Serial No. 872,630.

To all whom it may concern:

Be it known that I, RAYMOND G. HANNA, a citizen of the United States, residing at New York, in the county of New York and State of New York, have invented a new and useful Twin-Saddle Attachment for Motor-Cycles, of which the following is a specification.

The object of my invention is to provide 10 a twin-saddle attachment which may be readily attached to motorcycles, and particularly to provide a device of that character having novel laterally adjustable saddle posts or supports which are independently adjustable, so that if a lighter rider is on one side of the motorcycle, his saddle may be moved out farther from the machine and in that 15 way overcome the difference in weight between himself and his companion on the opposite side of the motorcycle.

It is a further object of my invention to provide a twin saddle attachment that is adjustable longitudinally of the motorcycle.

It is also an object of my invention to 25 provide a twin saddle attachment adapted for carrying either the ordinary motorcycle saddles, or seats of any character, interchangeably, and which affords means for the readiest attachment or adjustment of such 30 saddles or seats to the supporting frame of my invention.

It is also an object of my invention to provide an attachment having supporting means adapted to be fastened either to the lower 35 rear forks or to the lower part of the seat post mast as desired.

It is of course an object of my invention to provide a device in which the number of parts required have been reduced to the 40 smallest practical number to attain the objects set forth, and which has effective adjusting means, as more fully hereinafter set forth.

I attain these objects by the mechanism 45 illustrated in the accompanying drawings, in which—

Figure 1 is a side elevation showing my attachment mounted on a motorcycle; Fig. 2 is a front elevation of my attachment, partly in section; Fig. 3 is a section on line 50 3—3 of Fig. 2; Fig. 4 is a section on line 4—4 of Fig. 2; and Fig. 5 is a section on line 5—5 of Fig. 2.

Like characters of reference indicate like 55 parts throughout the several views.

Referring to the accompanying drawings,

I provide a transversely extending member 1, having a clamp 2 fastened at its central portion adapted to be in turn fastened to the saddle post of a motorcycle. Pivotaly 60 attached to the ends of member 1, preferably by means of clamps illustrated which are pinned and brazed to member 1, are obliquely disposed members 3, having threaded portions 4, as illustrated in Fig. 2, 65 adapted to engage with supporting members 5, and secured in place by lock nuts 6. The principal supporting elements of the device are preferably of tubing, though it is within the contemplation of my invention to substitute rods for tubing. Supporting members 5 preferably have brazed in their lower ends solid members 7 adapted to receive the end of a bolt, as illustrated in the drawings. Engaged to the lower ends of supporting 70 members 5, preferably by means of members 7 as illustrated are adjustable clamping means 8, preferably comprising opposite grooved members 8^a engageable to the motorcycle framework, and bolts 8^b ad- 75 justably fastening the attachment to motorcycle frame members. My attachment may be fastened to the rear forks of rigid frame machines or to the saddle post mast of spring frame machines, with suitable clamp- 80 ing means, the drawings accompanying this application disclosing my preferred construction. Adjustably attached to transversely extending member 1, on opposite sides of the motorcycle, are saddle or seat 85 supporting members 9. It is within the contemplation of my invention to mount either saddles or seats other than saddles on members 9. Members 9, it will be observed, are slidably laterally independently of each 90 other, thus permitting of proper adjustment for riders of substantially different weight.

In operation my twin saddle attachment as a whole is longitudinally adjustable, it 100 being shown in its rearward position in Fig. 1, with clamp 2 extending rearwardly relative to the saddle post. By reversing the clamp 2 so as to extend forward from the saddle post, and moving clamping means 8 105 correspondingly the attachment as a whole may be adjusted to a position longitudinally forward on the machine, the U-shaped central portion of member 1 permitting of this adjustment. Saddle or seat supporting 110 members 9 are adjusted in their relation to the center of the motorcycle so that if a

lighter rider is on one side of the machine, the member 9 on that side can be slid out laterally farther from the machine and clamped in position to overcome the weight 5 of the heavier rider on the opposite side of the motorcycle. Members 3 and 5 having a threaded engagement with each other are adjustable to different sizes of motorcycles and as to the distance they will extend from 10 the rear forks out.

What I claim is:

1. A twin saddle attachment comprising transversely extending saddle supporting means, saddle posts adjustably mounted 15 thereon, bracing members pivotally attached to the ends of the saddle supporting means, bracing members attached to and adjustable relative to the first-mentioned bracing members to allow for adjustment of the device to 20 different sizes of cycle frames, and having clamping means engaging the cycle frame.
2. A saddle attachment comprising a transversely-extending seat supporting member of inverted U-form at its central portion, 25 opposite seats mounted thereon, means for clamping the aforesaid seat-supporting member either rearwardly or forwardly of the seat post of the cycle, and bracing means supporting the ends of the seat-supporting 30 member from the cycle frame.
3. A saddle attachment comprising a transversely-extending seat supporting member, means for adjustably mounting seats thereon, means for adjustably fastening the seat supporting member to the cycle saddle post, and adjustable bracing means 35 pivotally engaging the outer ends of the seat supporting member and adjustably engaging lower portions of the cycle frame.
- 40 4. A saddle attachment comprising a transversely extending member, a clamp at its central portion adapted to reversibly engage the cycle saddle post, obliquely-disposed members pivotally mounted to the

ends of the transversely extending member, 45 clamping means adapted to be fastened to the lower framework of a cycle, and supporting means to which the last-mentioned clamping means are secured and having an adjustable connection with the obliquely-disposed members, substantially as described.

5. A twin saddle attachment comprising a transversely extending member, independently adjustable saddle supporting means 55 mounted thereon, longitudinally adjustable means clamping the transversely extending member to the cycle, vertically adjustable supporting means having a pivotal connection with the outer ends of the transversely extending member, and adjustable clamping means mounted to the lower ends of the aforesaid vertically adjustable means to fasten same to the cycle frame, substantially as described.

6. A twin saddle attachment comprising a transversely extending member, means for attaching same to a cycle frame, means capable of independent lateral adjustment for supporting twin seats on the transversely 70 extending member, obliquely-disposed members pivotally engaging the ends of the transverse member mentioned and having threaded end portions, supporting members adjustably engaging the obliquely-disposed 75 members, lock nuts engageable with the latter members, and clamping means supported by the lower ends of the supporting members mentioned and adapted to be fastened to the lower rear forks of a cycle, substantially as set forth.

In testimony whereof I hereunto affix my signature, in the presence of two witnesses.

RAYMOND G. HANNA.
